UNITED STATES PATENT OFFICE.

GEORGE A. JOHNSON, OF CHICAGO, ILLINOIS, ASSIGNOR TO WILLIAM H. MINER, OF CHAZY, NEW YORK.

SELF-CENTERING ROLLER-BEARING.

1,317,791.

Specification of Letters Patent. Patented Oct. 7, 1919.

Application filed October 12, 1918. Serial No. 257,838.

To all whom it may concern:

Be it known that I, GEORGE A. JOHNSON, a citizen of the United States, residing at Chicago, in the county of Cook and State 5 of Illinois, have invented a certain new and useful Improvement in Self-Centering Roller-Bearings, of which the following is a full, clear, concise, and exact description, reference being had to the accompanying 10 drawings, forming a part of this specification.

This invention relates to improvements in self-centering roller bearings.

One object of this invention is to provide 15 a simple, practical and relatively inexpensive roller bearing especially adapted for railway car side bearings and wherein is employed a minimum number of parts with an anti-friction roller that is self-centering 20 without the aid of springs or other parts likely to get out of order.

More specifically, the object of the invention is to provide an anti-friction roller side bearing for railway cars of a true cylindrical anti-friction roller type possessing all 25 the usual advantages of the true cylindrical roller bearing combined with the self-centering advantages of the usual type of rocker side bearing and without the disadvantages 30 usually accompanying either of said types.

In the art of anti-friction bearings, and particularly side bearings for railway cars, many efforts have been made to provide an anti-friction bearing for the bolsters of a 35 car and so designed that the anti-friction element will maintain a uniform distance between the opposed bearing surfaces of the bolsters and at the same time have the anti-friction element adapted to return to normal 40 position after the removal of the actuating pressure. With a true cylindrical anti-friction roller, it has heretofore been necessary to provide some additional means for returning the roller to central normal position 45 since, with the true cylindrical roller the roller is not permitted to rise up inclined tracks because of the necessity of maintaining the uniform heights. These additional means have generally included a spring or 50 springs arranged in a great variety of ways. As will be evident, the springs constitute the weakest element of the bearing and thereby shorten its life or require frequent 55 repair, aside from the additional first cost. With the rocker bearing of the usual type, 60

the permissible amount of travel of the anti-friction element has been restricted to a certain extent; the action has not entirely simulated that of a true cylindrical roller; and various other difficulties have been encountered in the successful operation of the rocker bearings due to the tendency of the rocker to become displaced or off center and from accumulations of cinders and other foreign matter in the bearing in such manner as to prevent the rocker from returning to central position automatically under the influence of gravity. With the present invention, I combine all the advantages of the anti-friction rollers with those of the rocker 65 60 65 70 75 80 85 90 95 100 105 110

bearings and eliminate the disadvantages. At the same time, I provide a bearing which comprises only two elements, the retaining casting and the roller itself, and at the same time design the parts so that the roller will be self-centered after each actuation.

In the drawings forming a part of this specification, Figure 1 is a vertical, sectional view of a side bearing applied to a railway car, the body and truck bolsters being also 80 shown in section. Fig. 2 is a vertical, sectional view, taken on the line 2—2 of Fig. 1. And Fig. 3 is a top plan view of the bearing shown in Fig. 1, with roll in dotted lines.

In said drawing, 10 denotes a truck bolster of a railway car and 11 an opposed body bolster and between which the improved side bearing is interposed. As shown in the drawing, the improved side bearing comprises a retaining member A and an anti-friction 85 90 95 100 105 110

element B. The retaining member A is preferably in the form of a casting and is formed at the bottom thereof with suitable perforated ears or flanges 12 by which the retaining member A is adapted to be riveted or otherwise secured to the truck bolster. The retaining member A is formed with end walls 13—13 that diverge slightly in an upward direction or, in other words, the end walls 13 are inclined in the position shown in Fig. 1, for the purpose hereinafter described. The member A is provided also with parallel side walls 14—14 and with a pair of longitudinally extending, horizontal, parallel bearing seats 15—15 on which are preferably applied steel inserts 16—16 to increase the wearing qualities.

The anti-friction element B comprises a true cylindrical portion 116, the ends of 110

which roll along the horizontal bearing seats hereinbefore referred to and as most clearly illustrated in Fig. 2. It will be noted that a sufficient portion of the roller bears on the 5 seats so as to obtain great strength and without danger of the roller crushing due to it being supported at points spaced too far apart and thereby permitting too great a bending moment to be imposed upon the 10 roller. At its center and adapted to be disposed between the horizontal bearing seats, the member B is provided with a preferably integral normally depending eccentric weight 17 curved on its under face as 15 indicated at 18 and having preferably flat faces 19-19 that extend tangentially to the curved surface of the roller proper. The element B is preferably cored, as indicated at 20, so as to facilitate the casting of the 20 roller and at its ends, the member B is provided with annular bosses 21-21 which are adapted to travel within longitudinally extending recesses or offsets 22-22 formed in the side walls of the retaining member A. 25 As shown in Figs. 1 and 2, the base member A is formed with vertical openings 23 adapted to permit entrance of the annular bosses 21 into said recesses 22 after which the upstanding tongues or flanges 24 of the 30 base member A are adapted to be hammered over into the position shown at 124 in Fig. 1. By making the retaining member A in the form of a malleable casting and constructing it in the manner described, the parts can be 35 locked against accidental disengagement after the roller has been assembled with the casting A.

The normal position of the anti-friction element with respect to the retaining member A is shown by the full lines in Fig. 1. As will be evident, upon relative horizontal movement between the two bolsters of the car, the roller will be given a true rolling movement along the cooperating horizontal 40 bearing seats until the limit of movement is reached, as indicated for instance, by the dotted lines in Fig. 1. The amount of permissible rolling movement will depend upon the diameter of the anti-friction element and 45 the inclined faces 19 of the eccentric weight 50 are so located with respect to the inclined end walls 13 of the base casting that said inclined edges 19 will bear flatly against the inclined end walls at the end of the rolling 55 movement of the anti-friction elements and as clearly shown in Fig. 1. As will be evident, as the anti-friction element is moved off center, the eccentric weight is lifted and will therefore automatically return the anti- 60 friction element to normal under the influence of gravity when the pressure is removed from the anti-friction element.

I wish to call attention also to another important feature of my invention. Heretofore, in many types of side bearings where-

in gravity is depended upon to return an element to normal position, as for instance, down an incline, it frequently occurs that cinders or other foreign matter will accumulate on the runways and the anti-friction 70 element will be jounced in such manner when not in actual operation as to bring the anti-friction element to rest at a considerable distance off center or normal position. As a result, when the anti-friction element is actuated, the permissible travel thereof falls short of the requirements and the bearing does not perform its proper function. By forming the depending eccentric weight of my roller in the manner disclosed and locating it with respect to the end walls as shown, it is impossible for my anti-friction element to get off center and be held there except for a very limited distance, to-wit, the shortest distance between an end wall and the depending eccentric weight. In other words, the distance which my anti-friction element can be accidentally held off center, due to accumulation of cinders, jarring of the bearing or other causes, is limited to any desired 90 degree and is dependent upon the spacing between the eccentric weight and the end walls of the casting. In actual practice, this amount of possible offsetting of the anti-friction element can be limited to such an extent as to always insure leaving ample permissible rotating movement of the roller to carry out the function of the bearing. As will be evident, any foreign matter that does 95 accumulate on the horizontal bearing seats 100 will be ground beneath the roller when it is actuated and will readily wash out through the openings 25 left in the ends of the base casting A.

From the preceding description, it will 105 be seen that my device can be manufactured at a relatively small expense; can be easily assembled and when assembled, the parts cannot become displaced or accidentally disassembled; the bearing consists of a minimum number of parts and embodies all the advantages of a true cylindrical anti-friction roller with the self-centering feature without the aid of extraneous means such as have heretofore been generally employed. 110

Although I have herein shown and described what I now consider the preferred manner of carrying out the invention, the same is merely illustrative and I contemplate all changes and modifications that 120 come within the scope of the claim appended hereto.

I claim:

In an anti-friction bearing of the character described, the combination with a base 125 casting having spaced, longitudinally extending bearing seats on its interior, said casting having also inclined end walls extending transversely of said seats, of an anti-friction roller supported at its ends 130

upon said bearing seats, said roller having
an eccentrically and integrally formed sec-
tion normally depending between said seats,
said section merging with the surface of the
5 roller by means of edges disposed tangential
to the curved surface of the roller, said tan-
gential edges being arranged to coöperate

with the inclined end walls of the base cast-
ing to limit the rolling movement of the
anti-friction element.

In witness that I claim the foregoing I
have hereunto subscribed my name this 9th
day of Oct., 1918.

GEORGE A. JOHNSON.
